Des. 222,380
Patented Oct. 19, 1971

222,380

PIZZA PIE CUTTER

Joseph Fraioli, Sr., New York, N.Y.
(300 Martine Ave., White Plains, N.Y. 10601)

Filed Apr. 22, 1970, Ser. No. 22,567

Term of patent 14 years

Int. Cl. D7—06

U.S. Cl. D44—29

FIG. 1 is a front elevational view of a pizza pie cutter, showing my new design;

FIG. 2 is a top plan view;

FIG. 3 is a right end elevational view;

FIG. 4 is a left end elevational view; and

FIG. 5 is a rear elevational view.

I claim:

The ornamental design for a pizza pie cutter, as shown.
